CLAIM

I claim the ornamental design for an air conditioner for electric panels, as shown and described.

DESCRIPTION

FIG. 1 is a front perspective view of the air conditioner showing my new design;

FIG. 2 is a back perspective view of the air conditioner of FIG. 1;

FIG. 3 is a front elevation view thereof;

FIG. 4 is a side elevation view thereof, the opposite side being a mirror image thereof;

FIG. 5 is a back elevation view thereof;

FIG. 6 is a top view thereof; and,

FIG. 7 is a bottom view thereof.
